UNITED STATES PATENT OFFICE.

CONRAD L. DRIEFER, OF SAN FRANCISCO, CALIFORNIA.

SAW-SET.

SPECIFICATION forming part of Letters Patent No. 678,648, dated July 16, 1901.

Application filed January 22, 1901. Serial No. 44,303. (No model.)

To all whom it may concern:

Be it known that I, CONRAD L. DRIEFER, a citizen of the United States, residing at 828 Minnesota street, San Francisco, in the county 5 of San Francisco and State of California, have invented certain new and useful Improvements in Saw-Sets; and I do hereby declare the following to be a full, clear, and exact description of said invention, such as will enable others skilled in the art to which it most 10 nearly appertains to make, use, and practice the same.

This invention relates to improvements in saw-sets, and particularly to saw-sets capable 15 of setting a plurality of teeth with one action.

The object sought to be accomplished is to provide means for setting alternate teeth of the saw in opposite directions with one action, so that the pressure on each tooth may be 20 equal and a perfect offset of the saw-teeth result.

In the drawings, Figure 1 is a side elevation of a saw-set constructed in accordance with this invention, the circular-saw gage attachment being in dotted construction. Fig. 2 is a similar view in front end elevation. Fig. 3 is a plan view from above of the bed of the saw-set below the line X X, Fig. 1, showing the plungers in operative position. Fig. 30 4 is a side elevation of Fig. 3, the parts being cut away on the line X' X', Fig. 3. Fig. 5 is an end of one of the plungers in its guide. Fig. 6 is a diagrammatic end elevation showing the circular-saw guide in position on the 35 periphery of a circular saw.

In the description with reference to the accompanying drawings the primary groups of mechanisms will be distinguished by a letter, the secondary mechanisms of these groups 40 being distinguished by the common letter strengthened by the addition of a numeral.

The handle-lever mechanism will be designated by the letter A, the bed mechanisms by the letter B, the gaging mechanisms by 45 the letter C, the spacing mechanism by the letter D, the circular-saw gage by the letter E, and the saw-blade by the letter F.

In construction the saw-set consists of two oppositely-acting lever-handles A A, fulcrumed on the pin B'. To control the throw of 50 these handles, the stop-screw A' is threaded through one handle for the other handle to

butt against, the lock-nut A² being provided to maintain the adjustment of the screw A'. The spring A³, set between the handles, maintains them in open-position. The ends of the handles extending into the bed B are provided with the plates A⁴, screwed thereto. 55

The bed B consists of a box-like structure suspended from the pin B' by the extensions 60 or links B², and the bed-plate B³ is divided and inserted into the grooves B⁴, provided in the frame of the bed. The bed-plate is made separate to facilitate the forming of the transverse channels B⁵, in which the plunger-guides B⁶ are secured by the wing-screws B⁷, threaded into their bottoms and operating in the slots B⁸. The bed B is divided vertically by the throat B⁹, into which the saw-blade F is inserted. 65

The spacing-gage consists of the stud-bolt C', extending from the bed on the right-hand side, the gage-disk C² being threaded onto the bolt C' and locked in the desired position by the lock-nut C³. 70

The space-counting gage consists of the lever D', fulcrumed in the attaching-lug D², screwed to the standard B² on the left-hand side of the bed. Hinged to the member D' is the pawl D³, and the gage-screw D⁴ is provided above the fulcrum of the member D' to butt against the head of the pin B'. 75

The setting mechanisms consist of two oppositely-acting plungers B¹⁰, rectangular in shape, sliding within guides B⁶. The faces 85 B¹¹ of the plungers B¹⁰ are formed to impart the proper offset to the saw-teeth F, the rear end of the plungers being provided with the recess B¹², into which the plates A⁴ extend.

The circular-saw gage E consists of a yoke 90 member E', straddling the bed B, pivoted between the lugs E² on the plate E³, secured to the bed-plate by the wing-screw E⁴. The member E' is regulated with reference to the periphery of the circular saw by the screw 95 E⁵, threaded in its head E⁶ and butting against the plate E³.

Having thus described the construction, the operation is as follows: The saw-set is placed with the throat B⁹ straddling the saw-blade 100 F, the gage C being upon the right-hand side, the spacer D being in the position shown in Fig. 2, (the pawl D³ resting in the throat of a saw-tooth.) The gage-disk C² is adjusted to

also rest in the throat of a saw-tooth and locked in position by the lock-nut C³. The plungers B¹⁰ are now adjusted (see Fig. 3) so that two teeth F' are brought into line with the faces B¹¹, the plungers being now locked in this position by the wing-screws B⁷, the channels B⁵ serving to keep the plunger-guides in line. The plates A⁴ are sufficiently wide to permit the adjustment of the plungers laterally without disengagement. The curve of the saw-teeth is regulated by limiting the throw of the handles A by setting the screw A' to the desired pitch. Compression of the handles A advances the plungers B¹⁰, imparting the proper offset to two of the teeth F'. Having completed one action, the whole mechanism of the saw-set is advanced the two succeeding saw-teeth by throwing the head of the member D' forward until the regulating-screw D⁴ (previously set) butts against the head of the pin B', the pawl D³ following up the mechanism, when the member D' is released and returned to normal position by the spring D⁵, the head of which is secured under the head of the attaching-screw D⁶ of the lugs D². The spring D⁷ may be dispensed with, but assists the action of the pawl D³.

To support the mechanism when the last tooth of the saw is reached, the extension B¹³, Fig. 3, on the bed is provided. The reason for this is obvious.

In handling circular saws were the depth of the throat B⁹ alone depended upon the arc of the saw would throw the teeth above the line of the plungers. To regulate this, the attachment E is set so that the head E⁷ of the yoke member E' rests upon the periphery of the saw, the blade-guide E⁸ resting in the throat of a tooth, (see Fig. 6,) the depth of the throat B⁹ being thus regulated by the screw E⁵.

It is obvious that the saw-teeth may be set at irregular intervals, as is desirable in some classes of hack-saws. In an experienced or steady hand the spacing mechanism D could be dispensed with. Certain mechanical changes, such as a micrometric adjustment of the guides B⁶, by extending a screw from the side of the bed B with swivel attachment to the guide B⁶, may be made. Further, this invention does away with the necessity of the usual anvil in saw-sets—in itself a substantial improvement. However, should an anvil be desired it could easily be made a separate attachment and be applied in front of the plunger. It is also obvious that the invention is

equally advantageous in straightening the teeth—in fact, by using this invention the same teeth may be repeatedly set, straightened, and reset in the opposite direction without the least injury to the teeth. The teeth being set on a curve are much stronger than when bent at an angle by the impact of a hammer or the use of an anvil.

Having thus described this invention, what is claimed is—

1. In a saw-set or the like, an open-bottom bed member having grooves in its inner side walls, bed-plates fitting in said grooves and having a throat left between their inner ends, and upsetting members carried by said bed-plates; substantially as described.

2. In a saw-set or the like, a pair of handles pivoted upon a fulcrum-pin, links upon said fulcrum-pin, a bed suspended by said links, plungers carried by said bed, and connection between said plungers and corresponding ends of said handles whereby said plungers are operated by the movement of said handles; substantially as described.

3. In a saw-set or the like, a bed, a plunger slideable thereon, said plunger having a recess near its outer end, an operating-lever engaging the outer end of said plunger, and a plate upon said lever engaging said recess; substantially as described.

4. In a saw-set or the like, a pair of handles, a fulcrum-pin upon which said handles are pivoted, links upon said pin, a bed suspended by said links, setting members carried by said bed and having operative connection with the ends of the handles, and spacing mechanism supported by one of said links; substantially as described.

5. In a saw-set or the like, a pair of handles, a fulcrum-pin upon which said handles are pivoted, links upon said pin, a bed suspended by said links, setting members carried by said bed and having operative connection with the ends of the handles, a lug upon one of said links, a lever pivoted to said lug, a pawl upon said lever below its pivot, and a set-screw extending through said lever above its pivot; substantially as described.

In testimony whereof I have hereunto set my hand this 12th day of January, 1901.

CONRAD L. DRIEFER.
